UNITED STATES PATENT OFFICE

SAMUEL B. LESTNER, OF BROOKLYN, NEW YORK

INK EQUALIZER FOR PRINTING PRESSES

Application filed November 27, 1929. Serial No. 410,034.

This invention relates to ink fountains for printing presses.

One object of the invention is to provide an improved device of the character described in which an equalized feed of ink shall be supplied to the proper coating parts of a printing press, although the consumption of ink may vary at different points thereon.

Another object of the invention is the provision of a device of the nature set forth in which improved means permit a considerable saving in ink because the quantity of ink in the press may be adjusted according to substantially the precise amount that any given 15 job may require.

Another object of the invention is to furnish an improved device of the type specified in which the ink lasts the longest time without becoming stale, and stirring or driving of the 20 ink manually by the operator is dispensed with.

Another object of the invention is to construct a device of the class alluded to having improved means dividing the ink fountain to afford an ink supply section of a size to hold 25 the requisite amount of ink for an efficient feeding action, which means is easily adjusted to vary the size of said section; and also to provide an improved construction to facilitate the removal of said means from the fountain; and further to mount said means in an improved manner to permit the same to preferably automatically render said section substantially fluid tight with respect to the inclined bottom of the ink fountain, and still further, to provide an improved construction 30 that permits easy presetting of said means according to the size of the said section that is required and to permit the same to be rapidly reset at will, or even to cause the said means to constantly press the ink into feeding relation.

A further object of the invention is to provide a device of the type mentioned having 35 few and simple parts, which is inexpensive to manufacture, rugged, reliable, and efficient in use to a high degree.

Other objects and advantages of the invention will become apparent as the specification 40 proceeds.

With the aforesaid objects in view, the invention consists in the novel combinations and arrangements of parts hereinafter described in their preferred embodiments, pointed out in the subjoined claims, and illustrated on the annexed drawing, wherein like parts are 55 designated by the same reference characters throughout the several views.

In the drawing:

Figure 1 is a plan view of a device embodying the invention showing the application of the same to a printing press, of which a portion is disclosed.

Fig. 2 is an enlarged view in vertical section of the same taken on line 2—2 of Fig. 1.

Fig. 3 is a fragmentary view in elevation showing details of the invention including the means for initially setting the blade.

Fig. 4 is a view in vertical section taken on line 4—4 of Fig. 3.

Fig. 5 is a fragmentary detail of parts of the fountain adjusting means in modified form.

Fig. 6 is a fragmentary view of a portion of the same.

The advantages of the invention as here outlined are best realized when all of its features and instrumentalities are combined in one and the same structure, but, useful devices may be produced embodying less than 80 the whole.

It will be obvious to those skilled in the art to which this invention appertains, that the same may be incorporated in several different constructions. The accompanying drawing, therefore, is submitted merely as showing the preferred exemplification of the invention.

Printing presses of various types, among which may be mentioned the so called Kelly press, are constructed with an ink fountain with which an ink distributing roller, or an equivalent device, is in communication. Even though the job to be printed is a small one, a considerable amount of ink must be placed into the fountain to assure the proper feed of the ink therefrom, since the feed occurs by gravity, and furthermore, the density of the ink may vary for work of various kinds,

and also the amount of ink to be received from the fountain at various points therealong, as is well known in the art. Consequently a considerable waste of ink occurs, as 5 in cleaning the fountain, and because the ink changes in density after exposure to the air for a certain length of time, and must therefore be discarded. Furthermore, the operator must continually watch the ink and press the same 10 down toward the distributing roller, especially at those points of the fountain where the consumption of ink is greatest. Where the fountain is disposed beneath the table of the printing press, the operator must insert 15 his hand, and runs the risk of injury thereto by the moving parts of the machinery, and also he may soil with the ink the carrier belts that supply the paper sheets so that the latter will in turn become stained. By this invention, it is sought to overcome these handicaps and to diminish the amount of work and 20 attention required of the operator.

Generally described, the invention provides means which may be in any suitable form, as, 25 for example, a blade to divide the ink fountain of a printing press into two sections, but one of which is in communication with an ink distributing roller, this section alone receiving the ink. This blade is in relative 30 proximity to the said roller, and thus causes the latter to stir all the ink thoroughly, due to the rotation of the roller. The blade is adjustable to vary the size of the communicating section according to the amount of 35 ink to be received therein, which can be readily estimated by the printer. For this purpose the blade can be mounted for movement in various ways in the fountain, but in all cases, it is preferably stationary, although 40 it can be adjusted from time to time as the ink in the fountain diminishes. The manner of mounting the blade can vary, but for purposes of illustration, I show a plurality of 45 bearings on the fountain in which the blade is pivotally mounted to swing toward or away from the roller. In every case, the blade is in contact with the inclined bottom of the fountain, and it may be moved manually into the said contact, or automatically by reason 50 of its weight, or by spring means. To facilitate presetting of the blade, a suitable indicating means, such as, for instance, a handle, and suitable coacting parts, as a spring, may co-operate, thus permitting also an easy resetting of the blade. To permit the blade to be 55 easily cleaned, it is removable bodily from the fountain by making one of the bearings relatively movable, in which case the other bearing may be rigid or stationary, and no 60 parts may become lost. If desired the blade may be made to automatically press on the ink and take up the consumption thereon. Thus the level of the ink may be maintained. In 65 any event, this invention contemplates a closer and more extended contact between the

ink and the distributing roller than has been heretofore accomplished.

Referring in detail to the drawing 10 denotes a portion of a printing press with which the invention is used. This may include a 70 bottom 11 and side walls 12 and 13. Journaled in the side walls is an ink distributing roller 14 or other ink distributing member. Contacting the roller 14 may be other ink distributing rollers 15. The wall 11 has a portion 16 extending upward at an incline providing a fountain 17 with which the roller 14 is in communication. The bottom of the fountain is constituted of a flat member 18 secured by screws 19 and having a thin resilient portion 20, the edge of which is relatively close to the roller 14. The clearance space 21 governs as to the quantity of ink that will be received by the said roller from the fountain. The quantity of ink to be received by the roller 14 will vary at different points therealong, depending on the density of the printed matter at the corresponding points. To adjust the feed of ink accordingly, a plurality of spaced arms 22 are pivoted on a rod 23 that extends lengthwise of the fountain and is set into a recess 24, with the said arms beneath the adjustable fountain portion 20. The free ends of the arms are adjacent to the edge of the portion 20, and co-operating therewith are a plurality of spaced screws 25, whose conical ends contact the ends of the undersides of the arms, there being one screw for each arm, and each screw being separately actuated to move its arm, and in turn adjust the corresponding parts of the portion 20 in its clearance with the roller 14. The above description is given not with the intention of limiting the invention to any particular printing press construction, but rather to clearly indicate one possible application of the same, and to render the peculiar problems that are overcome by this invention clearly understood. It may be added that in certain types of printing presses, a table 26 is disposed over the fountain 17, and this table furthermore has carrier belts 27 for the paper guided on pulleys 28, 29 and the idlers 30, so that these carrier belts on the underside of the table are in comparatively close proximity to the fountain. Consequently, if the operator has to manipulate or feed the ink in the fountain while the press is in operation, his hand is in danger of being injured, and he may soil the carrier belts with ink, causing the sheets of paper to be stained. But even apart from that, he would suffer the annoyance of having to watch a partially concealed ink fountain, and having to insert his arm in an inconvenient position to move the ink in the fountain toward the roller. These inconveniences and dangers are avoided by my invention.

31 indicates a device embodying the invention and including any suitable means 130

such as a blade 32 that extends longitudinally of the fountain 17, between the walls 12 and 13 thereof, and divides the fountain into a pair of sections 33, 34. For this purpose, 5 the blade is in contact with the bottom of the fountain, and only the section 34 is in communication with the ink distributing roller 14. The said blade is ordinarily in relative proximity to the said roller, as shown.

10 The blade 32 may be made in various shapes, though it is preferably cut of sheet metal and may be flat, and substantially rectangular.

To mount the blade, a bar 35 extends therealong, and has end trunnions 36, 37 journaled in bearings 38, 39 that may be mounted on the end walls 12, 13 of the fountain. The bearing 38 is, preferably rigidly secured, while the bearing 39 is movable to permit release of the blade from the fountain. To accomplish this end the bearing 39 may be constructed in various ways, but one of which is indicated. It can be made a part of a bracket 40 that is mounted to be removable 20 from the fountain. For this purpose the bracket may have slots 41 that receive screws 42, which secure the bracket to the wall 13, and are so arranged that upon loosening the screws 42, the bracket may be removed from 25 the said wall. The bearing 39 is then free, so that the bar 35 and the blade 32 may be together removed from the fountain by a motion that is upward and endwise away from the bearing 38, so that the trunnion 36 30 may be released. The screws 42 are never removed from the machine, and the bearing 39 and its bracket structure always move with the bar and blade so that it cannot be misplaced or lost. No manipulation is required 35 of the bearing 38.

The blade 32 can thus be pivoted with respect to the said bearings toward or away from the ink roller 14, whereby the volume of section 34 can be varied according to the 40 amount of ink to be contained therein. A feature of the invention is that this movement of the blade can be accomplished wholly from a side of the machine, and in a convenient manner. Thus a handle 43 is 45 mounted on the bar 35 in a conveniently accessible position at a side of the machine, so that the blade can be moved without inserting the hand beneath the table. By its direction, this handle may indicate the relative position 50 of adjustment of the blade. This effect may be aided by the use of co-operating resilient means, as, for instance, the leaf spring 44 that is supported on the feet 45 of the bracket 40, and to which the said spring may 55 be secured at 46. The adjacent end portion 60 of the bar is of octagonal cross section at 47, providing surfaces at 45° to coat with the spring and aid in setting the blade.

In order to retain the lower edge of the 65 blade 32 in contact with the bottom of the

fountain, the blade is mounted in movable relation on the bar 35. For this purpose, it may have slots 48 therein, through which pass the thumb screws 49 that are threaded into the bar. These screws may be tightened for a predetermined setting of the blade, or they may be loose to permit the blade to drop by gravity into contact with the bottom of the fountain, or to be pressed into contact therewith, as by coil compression springs 50 taking around rods 51 extending from the bar 35 and passing through suitable holes in lugs 52 struck from the blade 32. The springs thus act between the lugs and the bottom of the bar 35 to move the blade downward automatically. Two or more of the springs 50 may be spaced along the blade. To lift the blade against the force of the springs, a fingerpiece 53 may be secured to the same. 75 80 85

The operation of the device will be clear from the foregoing description, and it will therefore suffice to add that the ink is placed in section 34 of the fountain 17. Due to the reduced cross sectional area of this section, 90 the ink will build up in height so as to assure a good gravity feed, and furthermore, to equalize the distribution of ink even though more ink may be consumed at one point than at another. The roller 14 also causes a churning action on the entire body of ink. This results because the blade is in relative proximity to the roller. Furthermore, there may be a comparatively narrow throat section *a* 95 through which the ink is strongly pressed frictionally by the roller downward into section *b* to cause a reliable feed of ink. If the ink has been materially consumed, the operator manipulates the handle 43 to move the blade 32 further forward toward the roller 100 105 110 115 120 125 130 135 140 145 150 155 160 165 170 175 58 that is threaded into a bushing 59 fixed to the spring, the end of the screw abutting the blade. To afford a good bearing with the screws, the blade has projecting cam portions 60 along which the ends of the said screws may move, and these portions may be formed by striking lugs from the blade. The action of the spring 56 is clearly such as to constantly compress the ink against the roller 14. The 10 tension on the springs may be varied by the screws 58, and if desired, the tension may be made greater for a denser ink and less for a relatively fluid ink.

I claim:

15 1. A device of the character described, including, in combination with a printing press having an ink fountain extending therealong, and an ink distributing roller in communication with the fountain, of relatively stationary means dividing the fountain lengthwise into two sections, but one of which is in communication with the roller.

20 2. A device of the character described, including, in combination with a printing press having an ink fountain extending therealong, and an ink distributing roller in communication with the same, of a member within the fountain and extending lengthwise thereof to divide the fountain into two sections, but 25 one of which is in communication with the roller, the said member being relatively stationary and in comparatively close proximity to the roller to cause the latter to effectively stir the ink in the communicating section.

30 3. A device of the character described, including, in combination with a printing press having an ink fountain extending therealong, and an ink distributing roller in communication with the fountain, of relatively stationary means dividing the fountain 35 lengthwise into two sections, but one of which is in communication with the roller, and other means mounting the first mentioned means in the fountain and permitting easy removal 40 thereof from the fountain.

45 4. A device of the character described, including, in combination with a printing press having an ink fountain extending therealong, and an ink distributing roller in communication with the fountain, of relatively stationary means dividing the fountain lengthwise into two sections, but one of which is in communication with the roller, associated 50 bearings for said means in proximity to the ends thereof for pivotally mounting the same for adjustment toward or away from the said roller, one of said bearings only being movable to release the said means, and permit disengagement of the same from the other bearing 55 for bodily removal of said means from the fountain.

60 5. A device of the character described, including in combination with a printing press having an ink fountain extending therealong, and an ink distributing roller in communication

65 with the fountain, of relatively stationary means dividing the fountain lengthwise into two sections, but one of which is in communication with the roller, spaced 70 bearings for said means pivotally mounting the same for adjustment toward or away from the said roller, and other means to retain the first mentioned means in adjusted position and in the relatively stationary relation.

75 6. A device of the character described, including, in combination with a printing press having a fountain extending therealong, and an ink distributing roller in communication therewith, of a blade dividing the fountain into a plurality of sections only one of which is in communication with the said roller, and means permitting adjustment of the blade toward or away from the roller to vary the size of the communicating section according to the amount of ink to be contained therein.

80 7. A device of the character described, including, in combination with a printing press having a fountain extending therealong, and an ink distributing roller in communication therewith, of a blade dividing the fountain into a plurality of sections only one of which is in communication with the said roller, and means permitting adjustment of the blade toward or away from the roller to vary the size of the communicating section according to the amount of ink to be contained therein, said means including bearings in proximity to the ends of the blade for pivotally mounting the same for the adjusting movement, the bearings being so associated with the blade and but one of the bearings being movable to permit the removal of the blade from the fountain.

85 8. A device of the character described, including, in combination with a printing press having a fountain extending therealong, and an ink distributing roller in communication therewith, of a blade dividing the fountain into a plurality of sections only one of which is in communication with the said roller, and means permitting adjustment of the blade toward or away from the roller to vary the size of the communicating section according to the amount of ink to be contained therein, the said fountain having an inclined bottom, said blade being movable with respect to the said means to contact the bottom of the fountain in any position therein.

90 9. A device of the character described, including, in combination with a printing press having a fountain extending therealong, and an ink distributing roller in communication therewith, of a blade dividing the fountain into a plurality of sections only one of which is in communication with the said roller, and means permitting adjustment of the blade toward or away from the roller to vary the size of the communicating section according

to the amount of ink to be contained therein, the said fountain having an inclined bottom, said blade being automatically movable downward with respect to said means to contact the bottom of the fountain in any position of adjustment.

10. A device of the character described, including, in combination with a printing press having a fountain extending therealong, and an ink distributing roller in communication therewith, of a blade dividing the fountain into a plurality of sections only one of which is in communication with the said roller, and means permitting adjustment of 15 the blade toward or away from the roller to vary the size of the communicating section according to the amount of ink to be contained therein, the said fountain having an inclined bottom, and resilient means for moving the blade downward with respect to the first mentioned means to contact the bottom of the fountain.

11. A device of the character described, including, in combination with a printing press 25 having a fountain extending therealong, and an ink distributing roller in communication therewith, of a blade dividing the fountain into a plurality of sections only one of which is in communication with the said roller, and 30 means permitting adjustment of the blade toward or away from the roller to vary the size of the communicating section according to the amount of ink to be contained therein, said means including a resilient member, the 35 blade having coacting means to cause the resilient member to stop the blade in predetermined positions of adjustment.

12. A device of the character described including, in combination with a printing 40 press having an ink fountain extending therealong, and an ink distributing roller in communication with the fountain, of relatively stationary means dividing the fountain lengthwise into two sections, but one of 45 which is in communication with the roller, and other means to constantly press the first mentioned means toward the roller to cause the ink to be compressed in the communicating section.

50 13. A device of the character described, including, in combination with a printing press having an ink fountain extending therealong, and an ink distributing roller in communication with the fountain, of relatively 55 stationary means dividing the fountain lengthwise into two sections, but one of which is in communication with the roller, said means being curved in transverse section to follow the contour of said roller.

60 14. A device of the character described, including, in combination with a printing press having an ink fountain extending therealong, and an ink distributing roller in communication with the fountain, of relatively 65 stationary means dividing the fountain length-

wise into two sections, but one of which is in communication with the roller, and other means to constantly press the first mentioned means toward the roller to cause the ink to be compressed in the communicating section, and to move the said first mentioned means downward into constant contact with the bottom of the fountain.

In testimony whereof I affix my signature.

SAMUEL B. LESTNER.
